UNITED STATES PATENT OFFICE.

ARTHUR EDWIN LEIGH SCANES, OF ASHTON-ON-MERSEY, AND OTHO ROBERT VERITY, OF HALE, ENGLAND, ASSIGNEES, BY MESNE ASSIGNMENTS, TO WESTINGHOUSE ELECTRIC AND MANUFACTURING COMPANY, A CORPORATION OF PENNSYLVANIA.

CONDENSER.

Application filed November 25, 1918. Serial No. 264,029.

To all whom it may concern:

Be it known that we, ARTHUR EDWIN LEIGH SCANES, a subject of the King of Great Britain, and a resident of Ashton-on-Mersey, in the county of Chester, England, and OTHO ROBERT VERITY, a subject of the King of Great Britain, and a resident of Hale, in the county of Chester, England, have invented a new and useful Improvement in or Relating to Condensers, of which the following is a specification.

This invention relates to condensers and the like for use in connection with steam engines, turbines, evaporating plant and other apparatus, and has for its object to reduce the amount of metal employed in the construction of such devices.

Steam condensers comprise a shell or body portion with, in the case of surface condensers, tubes through or round which condensing water is circulated and, in the case of jet condensers, a water supply device or jet, and various other accessories such as pumps, inlet and outlet pipes, water boxes and the like. As hitherto constructed the whole of these parts are usually formed of metal, the shell or body portion together with various other parts being of cast-iron or steel.

According to the present invention, the shell or body and such other parts as may be desirable are formed of concrete, brick or other cementitious or clay material which in some cases may be reinforced with metal as employed in the well-known ferro-concrete construction. The inlet and outlet pipes, the pumps, tubes, manhole covers, water boxes and other accessory parts, which it is necessary or preferable to form of metal are attached by suitable joints, and if necessary to metallic seats embedded in or otherwise secured in the concrete or non-metallic parts of the condenser.

In cases where the engine or other apparatus with which the condenser is to be employed is supported on comparatively large concrete foundations, said foundations may be made hollow in such a way as to form the condenser shell or body, and by this means the space occupied by the entire plant may be reduced, and in many cases the cost of construction may also be reduced.

In order that the invention may be clearly understood it will now be described with

reference to the accompanying drawings 55 which illustrate various methods of carrying the same out in practice.

Fig. 1 is a longitudinal sectional elevation of a surface condenser constructed in accordance with the invention. Fig. 2 is a 60 section on the line II—II, Fig. 1, and Fig. 3 is a horizontal section on the line III—III, Fig. 1. Figs. 4 and 5 are views similar to Fig. 1 illustrating modifications. Fig. 6 is a detail sectional view hereinafter explained. Figs. 7 and 8 are vertical 65 sectional elevations illustrating the invention as applied to jet condensers.

Referring now to Figs. 1 to 3, the condenser therein illustrated is intended for use with a steam turbine, the exhaust of which is indicated at 1 and which is supported on concrete foundations 2. The foundations are constructed with a large 70 hollow space which forms the shell or wall 75 of the condenser, the upper opening or steam inlet 3 being provided with a metallic piece 4 grouted into the concrete which may form part of the bed-plate for the turbine. The tube plates 5 at the end of the condenser 80 shell are secured to metallic rings 6 also grouted into suitable openings leading to the hollow space within the foundations 2. The condenser tubes indicated at 7 extend 85 from one tube plate to the other and may be supported at suitable places by sagging plates 8 mounted on side supports 9 in a manner shown by way of example in Fig. 2, and a suitable stay 10 may be provided secured to the tube plates and sagging plates 90 as indicated in Figs. 1 and 3. The cover plates 11 for the water heads of the condenser may be made of cast iron or other metal, one of which is secured to the ring 95 6 at one end of the condenser and the other being bolted or otherwise secured to an annular part 12 which is bolted to the ring 6 at the other end of the condenser. The inlet and outlet for the circulating water are

led into the water head at one end, this being divided as indicated in Fig. 1 by a horizontal partition 13 so that the water passes through the tubes in the one direction to the other end of the condenser and then returns back through the other portion of the tubes 100 to the end at which it entered in the usual manner. The outlet for condensate is formed by a conduit 14 provided with a

metal flange or seating 15 to which the suction pipe from the condensing pump may be attached. One or more conduits 16 in the foundations provides an outlet through which air and non-condensable gases are extracted. 17 is a conduit through which the turbine may exhaust to the atmosphere when the condenser is out of service. A suitable amount of space is left around the condenser tubes at the sides as shown at 18 in Figs. 2 and 3 to permit of a passage round the condenser both for steam and for inspection purposes, admission thereto being obtained through the exhaust steam opening at the top or through the conduit 17, or a suitable man-hole and passage provided in the foundations not shown in the drawings.

Referring now to Fig. 4, the construction therein shown differs from that illustrated in Figs. 1 to 3 of the drawings in that the left-hand cover is also formed of part of the concrete foundations as indicated at 19, a man-hole with cover being provided at 20 to give access to the left-hand tube plate 5. The annular part 12 shown in Fig. 1 of the drawings which forms the right-hand water head in place of being made of metal is formed by a continuation of the foundations as shown at 21 and the right-hand cover plate 11 is secured against a suitable seating 22 by means of bolts or other suitable means. The tube plate 5 may be supported from the cover plate by tension stays 23. In this drawing an expansion piece 24 is indicated between the turbine exhaust 1 and the steam inlet 3 to the condenser, a similar expansion piece may of course be provided if necessary in the construction shown in Fig. 1.

Fig. 5 illustrates a construction in which the condenser does not actually form part of the foundations but the shell 25 is constructed of concrete formed with suitable openings for the entry of steam at 3 and for the removal of the condensate at 14. Seatings 26 are provided for the tube plates 5 which are held in position by a series of bolts 27 passing from end to end of the shell. Where the steam inlet 3 is provided the bolts for securing the tube plates may be attached to a metal part 28 embedded in concrete shell, the upper part of which forms a seating 29 to which the turbine exhaust or expansion piece may be secured. The covers 11 for the water boxes are secured against seatings 30 by bolts 31 passing from one end to the other of the shell or having their inner ends secured to the metal part 28 as shown near the top of the drawing.

The tube plate forms a comparatively large item in the cost of constructing a condenser and in large condensers it may be advantageously constructed in reinforced concrete in order to reduce the cost. The provision of the large number of orifices in

which the tubes are inserted renders it necessary, however, that attention should be given to the arrangement of the reinforcing material so that adequate strength may be provided without interfering with the tube openings. Also special provision must, of course, be made for fluid tight joints between the tubes and the plate. As an example showing how this part of the invention can be carried out in practice the reinforcing material may take the form of one or preferably a plurality of sheets of what is well known as expanded metal, the pitch or distance between the centres of the orifices in the metal being chosen to correspond with the distance desired between adjacent tubes. Obviously various materials may be used for reinforcing, for example a steel network having meshes of a proper pitch or plates perforated with holes in positions corresponding to those of the tubes in the tube plate may be employed. One method of connecting the tubes to the tube plate is shown in detail in Fig. 6 which is a fragmentary sectional view drawn to an enlarged scale of a ferro-concrete tube plate having a tube connected thereto. In this figure the concrete portion of the tube plate is indicated at 32 and the reinforcing metal is indicated at 33. The concrete is moulded round a tube 34 with flanged ends having its outer end screw-threaded internally as shown at 35. The internal diameter of the tube 34 corresponds with the external diameter of the condenser tube 36 which is secured in position by means of a thimble 37 provided with an internally projecting flange 38 which abuts against the end of the condenser tube, the thimble 37 is screwed into the end of the tube 34 and suitable packing 39 is placed between the inner end of the thimble and the shoulder formed on the tube 34 so that a fluid tight joint is provided. Other means for securing the condenser tubes to the tube plate may obviously be employed.

In Fig. 7 the invention is shown as applied to a jet condenser the outer wall of which is formed by the concrete foundations 40 of the plant. The steam inlet is indicated at 41, the water inlet at 42, the air outlet at 43 and the condenser outlet at 44. The water inlet is connected with a head 45 which may conveniently be formed of metal provided with a series of spray nozzles 46 of the ordinary type. The steam inlet 41 is furnished with a seating 47 to which the steam supply pipe or exhaust pipe can be connected.

In Fig. 8 a condenser of what is commonly called the counter-flow type is shown, the condenser receptacle is formed by a cavity of suitable size in the foundations 48 of the plant, the steam is admitted through the conduit 49 and the condensing water through the conduit 50, the air suction is indicated at

- 51 and the outlet for condensate at 52. A plate 53 divides the receptacle into two parts and is furnished with water orifices through which the cooling water passes to the lower 40
 5 part of the condenser, and suitable baffles 54 and 55 are supported within the condenser in any convenient manner. The plate 53 and baffles may conveniently be formed of concrete or like material if desired.
- 10 It will be understood that the general details of the condensers and accessory fittings may be of any usual or suitable description and that suitable provision is made for securing proper fluid tight joints of parts 45
 15 where necessary. Such constructional details are well known to those skilled in the art and no further description thereof is deemed necessary.
- The non-metallic portions of the improved 20 condensers are hereinabove described as consisting of concrete but it will be understood that brick or other cementitious material may be employed and is intended to be included in this term. The tube plates and 25 covers for the water boxes may also be in the case of large constructions be conveniently formed of the same material. The concrete may be reinforced if desired as in the well known ferro-concrete constructions and 30 where an abnormally high steam temperature is anticipated it is advantageous to protect some parts of the inside of the condenser from the direct action of the steam by the provision of a comparatively thin metallic 35 lining or by the use of glazed brick or the like.

We claim as our invention:—

1. In a surface condenser, having the shell

and hot-well made of cementitious material, a water box comprising a tube plate constructed of cementitious material and a plurality of parallelly disposed metallic reinforcing plates embedded in the cementitious material of the tube plate.

2. A tube plate for surface condensers 45 comprising a body portion composed of reinforced concrete and a sleeve having a flange embedded in concrete and adapted to receive a condenser tube.

3. A tube plate for surface condensers 50 comprising a body portion constructed of cementitious material having a plurality of parallelly disposed metallic re-enforcing plates embedded therein and a metallic sleeve extending through the concrete and 55 adapted to receive a condenser tube.

4. A tube plate for surface condensers comprising a body portion composed of concrete and a sleeve having flanged ends embedded in the concrete and adapted to receive a condenser tube.

5. A tube plate for surface condensers comprising a body portion composed of concrete and a sleeve having flanged ends embedded in the concrete and adapted to receive a condenser tube, the ends of said sleeve being substantially flush with the surface of said body portion.

In testimony whereof we have hereunto subscribed our names this 22nd day of August, 1918.

ARTHUR EDWIN LEIGH SCANES.
OTHO ROBERT VERTITY.
